UNITED STATES PATENT OFFICE.

CHARLES H. MYERS, OF PHELPS, NEW YORK.

WINDOW-BEAD FASTENER.

SPECIFICATION forming part of Letters Patent No. 280,756, dated July 3, 1883,

Application filed February 23, 1883. (Model.)

To all whom it may concern:

Be it known that I, CHARLES H. MYERS, a citizen of the United States, residing at Phelps, in the county of Ontario and State of New York, have invented certain new and useful Improvements in Window-Bead Fasteners, of which the following is a specification, reference being had therein to the accompanying drawings.

10 This invention relates to certain new and useful improvements in devices for detachably securing window-frame beads in position in the frame; and it has for its object to construct a device which shall be capable of admitting of the ready removal and replacement of such beads, whereby the window-sashes may be removed for the purposes of washing and repairing the same.

It consists in the employment of a nail or 20 tapering rod adapted to be driven permanently into the window-casing proper, in connection with a metallic socket and pivoted locking-nut, the peculiarities of which will more fully hereinafter appear.

25 In the accompanying drawings, forming a part of this specification, and on which like letters of reference indicate corresponding features, Figure 1 represents a side elevation of a portion of a window-frame bead; Fig. 2, a 30 vertical sectional view, taken diametrically through the socket and locking-nut, showing a portion of the bead and window-casing proper; and Fig. 3, a like view to Fig. 1, showing the locking-nut removed and a modified 35 form of the construction of the socket.

The letter A designates a portion of an ordinary window-frame bead, and the letter B also a portion of the frame proper.

40 The letter C designates a nail or pointed wire adapted to be driven permanently into the casing proper, and provided in some instances with a serrated or spurred point, whereby it is more securely held in the wood against longitudinal withdrawal. Said nail, 45 at its outer end, is provided with a neck, C, and a head, c', over which is adapted to fit a locking-nut, D, the same consisting of a short piece of metal having a hub, d, and thumb-pieces E, projecting therefrom. The outer end 50 of the said hub is provided with a slot or depression, which serves to receive the point of a screw-driver, for a purpose which shall presently appear.

The letter F designates a metallic disk or socket, the same consisting of an annulus provided with screw-holes, by which it is secured in place, and of a bottom, F'. Said bottom is provided with a central aperture, through which passes a nail, C, and from said aperture extend, at diametrical points, slots f, 55 agreeing in width with the thickness of the thumb-pieces of the locking-nut. Each half of said bottom F', on its outer side, is inclined in opposite directions, forming a cam-face, which serves to allow the locking-nut to be 60 easily turned, and which acts to more firmly bind the bead to the casing proper when the nut is turned at right angles to the slots f. When it is desired to remove the bead, the 65 said nut is rotated until its thumb-pieces are coincident with the slots f, thereby admitting of the bead's being slipped over the same, this being done by applying the hand to the thumb-pieces or a screw-driver to the slot in the end of the hub. 70

75 It will be observed from Fig. 2 of the drawings that the bead is recessed, in order to receive the socket and bring the outer face thereof flush with the face of the bead. The socket indicated in Fig. 3 of the drawings is 80 provided with lugs on its periphery, which serve to prevent it from turning in the bead, and which are used in lieu of the screws, as shown in Fig. 1.

Having thus fully described my invention, 85 what I claim as new, and desire to secure by Letters Patent, is—

1. The combination, in a device for detachably securing a window-frame bead, of the fixed nail or stud having a pivoted locking-nut and a slotted socket, against which the nut is adapted to bear, substantially as shown and described. 90

2. The combination, in a device for detachably securing a window-frame bead, of a fixed nail having a spurred point and a pivoted locking-nut, with the slotted socket having a cam-shaped face, against which the nut is adapted to bear, substantially as shown and described. 95

In testimony whereof I affix my signature in presence of two witnesses.

CHARLES H. MYERS.

Witnesses:

CHAS. D. DAVIS,
EDWIN L. YEWELL.
